J. T. AND R. A. CAREAGA,
C. M. CAREAGA, EXECUTRIX OF R. A. CAREAGA, DEC'D.
EXPANDING PROJECTILE,
APPLICATION FILED JULY 10, 1918.
1,405,276. Patented Jan. 31, 1922.

UNITED STATES PATENT OFFICE.

JOHN T. CAREAGA AND RAMON A. CAREAGA, OF SAN JOSE, CALIFORNIA; CORA M. CAREAGA EXECUTRIX OF SAID RAMON A. CAREAGA, DECEASED.

EXPANDING PROJECTILE.

1,405,276.

Specification of Letters Patent. Patented Jan. 31, 1922.

Application filed July 10, 1918. Serial No. 244,287.

To all whom it may concern:

Be it known that we, JOHN T. CAREAGA and RAMON A. CAREAGA, citizens of the United States, residing at San Jose, in the 5 county of Santa Clara and State of California, have invented certain new and useful Improvements in Expanding Projectiles; and we do hereby declare the following to be a full, clear, and exact description of the 10 invention, such as will enable others skilled in the art to which it appertains to make and use the same.

The object of the invention is to provide a relatively simple and comparatively inexpensive expanding projectile for use in warfare and more especially designed as a means of destroying or removing barbed wire entanglements and attacking troops in close formation, and to that end the 15 same consists in a construction, combination and relation of parts hereinafter indicated, it being understood however that changes in form, proportion, material and details of construction may be resorted to 20 within the scope of the appended claims without departing from the spirit of the invention.

In the drawing:

Figure 1 is a side view of a projectile and 30 shell embodying the essential features of the invention.

Figure 2 is a longitudinal sectional view of the projectile.

Figure 3 is a similar view showing the 35 same in dotted lines with the parts in their expanded relation.

Figure 4 is a transverse section on the plane indicated by the line 4—4 of Figure 3.

Figure 5 is a sectional view on the plane 40 indicated by the line 5—5 of Figure 3.

Figure 6 is a sectional view of the projectile base and an auxiliary sleeve shrunk or threaded thereon.

The projectile, which may be of any suitable or approved material, is provided with 45 a base 10 with which are pivotally connected a plurality of expanding elements 11, any desired number of which may be employed and which are normally held in a contracted 50 or collapsed relation as shown in Figures 1 and 2 by an encircling retaining band 12 of which, however, a plurality may be employed if found desirable, and which may be of any suitable material capable of with- 55 standing the necessary tensile strain incident

to the centrifugal tendency of the expanding elements 11 due to the rifling of the gun by which a rotary movement is imparted to the projectile.

Within the body of the projectile formed 60 by the expanding elements is formed a chamber 13 for an expanding charge of T. N. T. or other explosive, said chamber being produced by the registration of a plurality of depressions formed respectively in said expanding elements. There has further been provided a passage 14 in which an igniting fuse may be placed and lighted before the projectile is placed in the gun, the length of the fuse being determined according to 70 the distance it is desired to have the projectile travel before the charge in the chamber 13 explodes and throws the arms outwardly. It will be understood that any suitable means may be employed for pivotally connecting 75 the elements with the base, such as the rivets indicated at 15, and that the base of the projectile may be arranged in a shell 16 containing the propelling charge 17, as shown in Figure 1, or may be fitted with a rifling 80 band 18 shrunk or threaded in place where a separate propelling charge is employed.

It will be obvious that a projectile of this type may be adapted to various types of guns and may be made of various sizes, lengths, 85 diameters and the like, the object being to so arrange the parts that the expanding charge will be detonated before the projectile reaches the objective so as to approach and contact with the objective in the expanded 90 position indicated in Figure 3. As ordinarily a projectile is given a rotary movement, due to the rifling in the gun, the centrifugal action will completely expand the elements and the rotary motion will be continued so 95 that the device will have tearing action in encountering barbed wire entanglements and the like to the end that the maximum efficiency in destroying the same may be attained.

Preferably the base of the projectile is extended beyond the contour peripherally of the expanding elements to form a stop shoulder 19 which serves to limit the expansion of the elements to a position which is transverse to the line of flight or is radial with reference to the axis of the projectile.

Having described the invention, what is claimed is:

1. An expanding projectile having a base 110

- provided with a reduced forward end portion cut to provide pivot ears, arms pivotally connected with the pivot ears and when swung into engagement forming a split body for 5 the projectile of substantially even diameter with the reduced forward end portion of the base, the inner portions of the arms being cut to provide recesses forming a charge receiving 10 pocket having a passage extending therefrom through the outer end of the body for receiving a fuse to ignite the charge in the pocket, and a breakable band positioned about the body to retain the arms in engagement, the arms engaging the base when 15 thrown outwardly and limited in their outward movement by the base.
2. An expansion projectile comprising a base having an enlarged rear end portion

forming an abutment, a body formed of sections pivotally connected with the forward 20 end portion of the base and limited in their outward swinging movement through engagement with the abutment shoulder formed by the enlarged rear end portion of the base, the body having a charge receiving 25 pocket for receiving a charge to throw the arms outwardly, and means for releasably holding the arms in a retracted position.

In testimony whereof we affix our signatures in presence of two witnesses.

JOHN T. CAREAGA.
RAMON A. CAREAGA.

Witnesses:

JOHN W. SULLIVAN,
S. H. BAUMAN.
